REFRIGERATION

Albert R. Thomas, deceased, late of Evansville, Ind., by The National City Bank, administrator, Evansville, Ind., assignor to Servel, Inc., New York, N. Y., a corporation of Delaware

Application October 25, 1944, Serial No. 560,213

19 Claims. (Cl. 62—119)

1

The present invention relates to improvements in absorption refrigeration systems and more particularly to apparatus for transferring non-condensable gases from one part of the system to another part thereof.

While the apparatus of the present invention may be applied to any two-pressure absorption refrigeration system it is particularly adapted for use with a system of the type illustrated and described in the prior patent to Thomas et al., No. 2,282,503, entitled Refrigeration. The absorption refrigeration system illustrated in the prior patent operates in a partial vacuum and utilizes water as a refrigerant and a saline solution as an absorbent. In such a refrigeration system non-condensable gases may accumulate in the various elements of the system which must be purged periodically. The exact cause of the generation of such non-condensable gases or the place where such gases are generated is not fully understood but the gases appear in all parts of the system and accumulate in the condenser and absorber. As the condenser operates at a higher pressure than the absorber the non-condensable gases may be purged more easily from the condenser than from the absorber. Furthermore, the presence of such non-condensable gases in the absorber decreases the efficiency of the refrigeration system to a greater degree than their presence in the condenser.

One of the objects of the present invention is to provide apparatus in an absorption refrigeration system for continuously withdrawing non-condensable gases from the low pressure side of the system and transferring them to the high pressure side of the system.

Another object is to provide apparatus of the type indicated which utilizes vaporized refrigerant in a Venturi tube to evacuate non-condensable gases from the absorber and transfer them to the condenser.

Another object is to provide apparatus of the type indicated which operates to vaporize refrigerant continuously and maintain the refrigerant vapor at a predetermined constant pressure.

Another object is to provide apparatus of the type indicated in which the pressure of the refrigerant vapor is maintained constant by a balancing column of liquid refrigerant of predetermined height.

Still another object of the invention is to provide apparatus of the type indicated which is of simple construction and efficient in performing its intended function.

These and other objects will become more

2

apparent from the following description and drawing. It is to be expressly understood, however, that the drawing is for the purpose of illustration only and not a definition of the limits of the invention, reference being had for this purpose to the appended claims. In the drawing, the single figure is a diagrammatic view of an absorption refrigeration system incorporating the novel features of the present invention.

10. Referring to the drawing, the invention is shown as applied to a two-pressure absorption refrigerating system similar to that illustrated and described in the prior Thomas et al. patent, referred to above. In a system of this type liquid refrigerant such as, for example, water is introduced into the upper part of an evaporator or cooling element 10 from a condenser 11 through a path of flow including a U-shaped tube 12 and a chamber 13. The liquid refrigerant evaporates 20 in evaporator 10 with consequent absorption of heat from the ambient, such as a stream of air flowing over the exterior surface of the tubes 14 and fins 15 of the evaporator. The refrigerant vapor formed in evaporator 10 flows to an absorber 16 in which the vapor is absorbed into a liquid absorbent such as, for example, a solution of lithium chloride or lithium bromide.

The absorption liquid enriched with refrigerant is conducted from the absorber 16 to a generator 17 in a path of flow including a conduit 18, liquid heat exchanger 19, conduit 20, vessel 21, and conduit 22. Within the generator 17 are disposed a plurality of riser tubes 23 enclosed by an outer shell forming a chamber to which steam is supplied through a conduit 24 from a suitable source of supply. The heating of the riser tubes 23 by the steam causes refrigerant vapor to be expelled from the absorbent and the expelled vapor is effective to raise the absorbent liquid by gas or vapor-lift action.

40. The expelled vapor passes from the upper ends of the riser tubes 23 into a vapor separator 25 and thence flows through a conduit 26 to the condenser 11 in which the vapor is liquefied. 45. Liquid refrigerant formed in condenser 11 flows into a sump 27 and from the sump flows into a lateral branch-conduit 28 and through the U-shaped tube 12 to the upper part of the evaporator 10, as explained above, to complete the 50 refrigerating cycle.

The raised absorption liquid from which refrigerant vapor has been expelled is conducted from the upper part of the generator 17 to absorber 16 to absorb refrigerant vapor, this liquid 55 being conducted to the absorber in a path of flow

including a conduit 29, liquid heat exchanger 19 and conduit 30. The heat liberated by absorption of refrigerant vapor in absorber 16 is taken up by a cooling medium such as, for example, water which flows upward through vertically disposed banks of pipes 31 in the absorber. The cooling water is introduced into the lower end of the banks of pipes through a conduit 32 and is discharged from the upper ends of the banks of pipes through a conduit 33. The conduit 33 is connected to condenser 11 so that the cooling water also may be utilized to effect cooling of the condenser 11. The cooling water is discharged from condenser 11 through a conduit 34.

The system operates in a partial vacuum with generator 17 and condenser 11 operating at one pressure and evaporator 10 and absorber 16 operating at a lower pressure. The pressure differential between the high and low pressure sides of the system is maintained by a liquid column in the up leg of the U-shaped tube 12 between the condenser 11 and evaporator 10 and a liquid column in the conduit 18 connecting the absorber 16 and the heat exchanger 19. A liquid column is also provided in the conduit 30 connecting the heat exchanger 19 and absorber 16. The liquid level in the U-shaped tube 12 is indicated by the reference character *x*; the liquid level in the vessel 21 connected to the conduit 18 through the heat exchanger 19 is indicated by the reference character *y*; and the liquid level in the conduit 29 connected to the conduit 30 through the heat exchanger 19 is indicated by the reference character *z*.

During operation of the refrigeration system non-condensable gases may accumulate in the various elements thereof. These non-condensable gases are probably formed by the chemical action of the fluids with the metallic parts of the system. The gases in the condenser tend to accumulate adjacent the outlet sump 27 and may to some extent be transferred through the U-shaped tube 12 to the upper part of the evaporator 10. Such gases in the evaporator 10 are swept into the absorber 16 by the refrigerant as it flows into the absorber at high velocity. The gases then accumulate in a layer at the bottom of the absorber 16. Thus the non-condensable gases accumulate adjacent the outlet of the condenser 11 and at the bottom and center of the absorber 16 and blanket off that portion of the condenser or absorber which they cover.

As the condenser 11 operates at a higher pressure than the absorber 16 the non-condensable gases may be withdrawn from the condenser with greater ease than from the absorber. For this reason an exhaust pipe 36 is connected between the condenser at a point adjacent its outlet and a suitable exhaust pump, not herein shown. The non-condensable gases are purged periodically from the condenser by the exhaust pump and preferably a manually operable stop valve 37 is provided in the exhaust pipe 36. As the non-condensable gases are purged from the condenser 11 it is necessary to provide some means for transferring the gases from the absorber 16 to the condenser. Furthermore, due to the difference in pressure in the condenser and absorber the same amount of the non-condensable gas will blanket off a greater portion of the absorber than of the condenser. As a result the accumulation of the gases in the absorber decrease the efficiency of the refrigeration system to a greater degree than when present in the condenser. It is, therefore, desirable to transfer the non-con-

densible gases continuously from the absorber to the condenser.

In accordance with the present invention apparatus is provided for cooperation with the refrigeration system to withdraw non-condensable gases continuously from the absorber 16 and transfer them to the condenser 11. The apparatus comprises a depending U-tube 40 having a down-leg 41 and an up-leg 42 connected by a loop at their lower ends. The upper end of the down-leg 41 of the U-tube 40 is connected to the bottom of the sump 27 at the outlet from the condenser 11. The end of the up-leg 42 of the U-tube 40 extends into an annular chamber 43 at one end of a Venturi tube 44. The end of the Venturi tube 44 is welded or otherwise sealed to the sides of the up-leg of the U-tube 40 adjacent its upper end and the Venturi tube tapers inwardly around the end of the U-tube to provide a Venturi throat 45. The Venturi tube 44 beyond the throat 45 gradually increases in diameter and its opposite end is connected to the conduit 26 extending between the generator 17 and condenser 11. Connecting the chamber 43 in the Venturi tube 44 and the interior of the absorber 16 is a conduit 46 which extends through the side wall of the absorber with its end positioned at the center and adjacent the bottom thereof where the non-condensable gases accumulate.

The lower looped end of U-tube 40 may be heated by any suitable means to vaporize liquid refrigerant therein. In the embodiment of the invention illustrated in the drawing the lower end of the up-leg 42 of the U-tube 40 has a number of helical coils 47 surrounding the base of the generator 17 in heat conducting contact therewith which constitutes a flash boiler for continuously vaporizing liquid refrigerant. While the apparatus is described as comprising separate parts it is in effect a continuous U-tube having its opposite ends connected at opposite sides of the condenser with a down-leg 41 connected to receive condensate from the condenser, an up-leg 42 having a Venturi throat 45 therein, a chamber 43 adjacent the Venturi throat connected to the absorber 16 through the conduit 46 and heating coils 47 at the lower end of the up-leg in heat conducting relationship with the base of the generator 17. The construction of the apparatus having been described in detail its mode of operation is explained as follows.

For purposes of description let it be assumed that no heat is being supplied to the generator 17 and the refrigeration system is inoperative. The opposite legs 41 and 42 of the U-tube 40 will have columns of liquid refrigerant therein of equal height. When steam is supplied to the generator 17 through the conduit 24 the refrigerant will be vaporized in the vertical riser tubes 23 and will rise through the vapor separator 25 and conduit 26 to the condenser 11. The refrigerant vapor will be condensed in the condenser 11 and flow by gravity into the sump 27 and down-leg 41 of the U-tube 40.

Simultaneously with the vaporization of the refrigerant in the generator 17 the liquid refrigerant in the coils 47 at the lower end of the up-leg 42 of the U-tube 40 will be vaporized by heat conduction from the generator. Such vaporized refrigerant in the coils 47 will expand and move upwardly in the up-leg 42 to displace the liquid refrigerant therein and cause it to spill over into the chamber 43 and flow through the conduit 46 to the absorber 16. This action will

for heating the generator to expel refrigerant vapor from absorption solution therein, a boiler arranged to receive liquid refrigerant from one of the high pressure elements of the system, means for heating the boiler to vaporize the liquid refrigerant therein, and a device utilizing the refrigerant vaporized in the boiler for withdrawing non-condensable gases from an element of the low pressure group and transferring the gases to an element of the high pressure group.

3. In an absorption refrigeration system of the type having one group of elements including an evaporator and absorber operable at low pressure and another group of elements including a generator and condenser operable at a higher pressure, means for maintaining the pressure differential between the groups of elements, means for heating the generator to expel refrigerant vapor from absorption solution therein, a boiler arranged to receive liquid refrigerant from one of the high pressure elements of the system, means for heating the boiler to vaporize the liquid refrigerant therein, and a Venturi tube utilizing the refrigerant vaporized in the boiler for withdrawing non-condensable gases from an element of the low pressure group and transferring the gases to an element of the high pressure group.

4. In an absorption refrigeration system of the type having an absorber operable at low pressure and a condenser operable at a higher pressure with means for maintaining the pressure differential between the condenser and absorber, the combination with said condenser and absorber of a boiler arranged to receive liquid refrigerant from the condenser, means for heating the boiler to vaporize the liquid refrigerant therein, and a Venturi tube utilizing the refrigerant vaporized in the boiler and connected to withdraw non-condensable gases from the absorber and transfer the gases to the condenser.

5. In an absorption refrigeration system of the type having one group of elements operable at low pressure and another group of elements operable at a higher pressure with means for maintaining the pressure differential between the groups of elements, the combination with said system of a boiler, a conduit arranged to supply liquid refrigerant from one of the high pressure elements of the system to the boiler and maintain a column of liquid therein to produce a pressure in the boiler higher than the pressure in the remainder of the system, means for heating the boiler to vaporize the liquid refrigerant therein, a Venturi tube connected to receive vaporized refrigerant from the boiler, and conduits connecting the venturi and elements of the high and low pressure groups, said Venturi tube utilizing the vaporized refrigerant for withdrawing non-condensable gases from the low pressure group through one of the conduits and transferring the gases to an element of the high pressure group through the other conduit.

6. In an absorption refrigeration system of the type having one group of elements operable at low pressure and another group of elements operable at a higher pressure with means for maintaining the pressure differential between the groups of elements, the combination with said system of a depending U-tube connected at its opposite ends to elements of the high pressure group, said U-tube being arranged to receive liquid refrigerant at one end and discharge refrigerant vapor from its opposite end, means for vaporizing the liquid refrigerant in the U-

tube, a conduit connected to an element of the low pressure group, and a device utilizing the vaporized refrigerant in the U-tube for withdrawing non-condensable gases from the element of the low pressure group through the conduit and transferring the gases to an element of the high pressure group.

7. In an absorption refrigeration system of the type having an absorber operable at low pressure and a condenser operable at a higher pressure with means for maintaining the pressure differential between the condenser and absorber, the combination with said condenser and absorber of a U-tube connected at its opposite ends to the opposite sides of the condenser, said U-tube being arranged to receive liquid refrigerant at one end and discharge refrigerant vapor from its opposite end, means for vaporizing the liquid refrigerant in the U-tube, a conduit connected to the absorber, and a device utilizing the vaporized refrigerant in the U-tube to withdraw non-condensable gases from the absorber through the conduit and transfer the gases to the condenser.

8. In an absorption refrigeration system of the type having one group of elements operable at low pressure and another group of elements operable at a higher pressure with means for maintaining the pressure differential between the groups of elements, the combination with said system of a U-tube connected at its opposite ends to elements of the high pressure group, said U-tube being arranged to receive liquid refrigerant at one end and discharge refrigerant vapor from its opposite end, means for vaporizing the liquid refrigerant in the U-tube, a conduit connected to an element of the low pressure group, and a Venturi tube utilizing the vaporized refrigerant in the U-tube to withdraw non-condensable gases from the element of the low pressure group through the conduit and transfer the gases to an element of the high pressure group.

9. In an absorption refrigeration system of the type having one group of elements operable at low pressure and another group of elements operable at a higher pressure with means for maintaining the pressure differential between the groups of elements, the combination with said system of a U-tube connected at its opposite ends to elements of the high pressure group, said U-tube being arranged to receive liquid refrigerant at one end and discharge refrigerant vapor from its opposite end, means for vaporizing the liquid refrigerant in the U-tube, a conduit connecting the U-tube and an element of the low pressure group, and a Venturi throat in the U-tube utilizing the vaporized refrigerant therein to withdraw non-condensable gases from the element of the low pressure group through the conduit and transfer the gases to an element of the high pressure group.

10. In an absorption refrigeration system of the type having an absorber operable at low pressure and a condenser operable at a higher pressure with means for maintaining the pressure differential between the condenser and absorber, the combination with said condenser and absorber of a U-tube connected at its opposite ends to the opposite sides of the condenser, said U-tube being arranged to receive liquid refrigerant from the condenser at one end and discharge refrigerant vapor to the condenser at its opposite end, a Venturi throat in the U-tube, and a conduit connecting the Venturi throat and absorber, said venturi utilizing the vaporized refrigerant in the U-tube to withdraw non-condensable gases from the ab-

continue until the liquid refrigerant in the up-leg 42 has been completely displaced by the vaporized refrigerant. The column of liquid refrigerant in the down-leg 41 of the U-tube 40 will tend to flow into the coils 47 to be vaporized therein. The feeding of the liquid refrigerant to the coils 47, however, will be opposed by the pressure of the vaporized refrigerant in the up-leg 42. Thus the pressure of the vaporized refrigerant in the up-leg 42 is balanced and maintained by the column of liquid refrigerant in the down-leg 41. As the refrigeration system continues to operate more condensate from the condenser will be fed to the sump 27 which increases the height of the liquid column in the down-leg 41 until its level is raised to the level of the lateral branch-conduit 28 where it over-flows into the U-tube 12 connected to the evaporator 10. It will be observed, therefore, that the lateral branch conduit 28 will maintain a column of liquid in the down-leg 41 of the U-tube 40 of a predetermined height as indicated by the reference character *h*. With a column of liquid in the down-leg 41 of a predetermined height the vaporized refrigerant in the up-leg 42 will be maintained at a pressure corresponding to the height of the liquid column.

The vaporized refrigerant in the up-leg 42 of the U-tube 40 will escape from its open end under pressure and pass through the Venturi throat 45. The flow of refrigerant vapor through the Venturi throat 45 entrains the media in the chamber 43 to evacuate the latter, the vaporized refrigerant and entrained media flowing through the Venturi tube 44 to the conduit 26 and into the condenser 11. The evacuation of the chamber 43 will continue until the pressure therein is less than the pressure in the absorber 16. When the pressure in the chamber 43 is less than the pressure in the absorber 16 the non-condensable gases adjacent the end of the conduit 46 will be drawn therethrough and into the chamber and pass through the Venturi tube 44 to the conduit 26 and into the condenser 11. During normal operation of the refrigeration system the liquid refrigerant will be continuously vaporized in the heating coils 47 at the lower end of the up-leg 42 of the U-tube 40 and the vaporized refrigerant will be forced under pressure through the Venturi tube 44 to withdraw non-condensable gases from the absorber 16 continuously and transfer the gases to the condenser 11. Periodically the non-condensable gases will be purged from the condenser 11 by means of the vacuum pump (not shown) which operates to evacuate the exhaust pipe 36 connected to the condenser 11 until the pressure in the latter is lower than the pressure in the condenser. The stop valve 37 in the exhaust pipe 36 then will be opened to connect the interior of the condenser 11 to the vacuum pump to withdraw the non-condensable gases. At the completion of a purging operation the stop valve 37 is closed.

It will be understood that the U-tube 40 will be so constructed and arranged as to adapt it for the conditions of the particular refrigeration system to which it is applied. For instance, the diameter of the up-leg 42 of the U-tube 40 must be so limited as to maintain the pressure of the vaporized refrigerant while providing a sufficient volume of vapor discharged from its end to create the desired vacuum in the chamber 43. It also will be understood by those skilled in the art that a nozzle may be provided at the upper end of the up-leg 42 if such a nozzle is found necessary. A specific example of the operating con-

ditions of the particular absorption refrigeration system to which the present invention is shown applied is described as follows. The absolute pressure normally occurring in the condenser 11 is one pound per square inch (1#/sq. in.) while the absolute pressure occurring in the absorber 16 is one-tenth of a pound per square inch (.1#/sq. in.). It has been found that by maintaining a refrigerant vapor pressure in the up-leg 42 of the U-tube 40 of four pounds per square inch (4#/sq. in.) absolute a sufficiently high vacuum may be maintained in the chamber 43 to continuously withdraw non-condensable gases from the absorber 16. In order to maintain a pressure of the refrigerant vapor of four pounds per square inch absolute a liquid column six feet high must be maintained in the down-leg 41 of the U-tube. This liquid column is maintained in the down-leg 41 by arranging the lateral branch-conduit 28 a distance of six feet above the bottom of the U-tube 40. The six foot head of liquid refrigerant in the down-leg 41 corresponds to a pressure of three pounds per square inch (3#/sq. in.) which in addition to the one pound per square inch occurring in the condenser 11 gives a total pressure of the refrigerant vapor of four pounds per square inch absolute.

It will now be observed that the present invention provides an apparatus for continuously transferring non-condensable gases from the low pressure side of the system to the high pressure side of the system. It will further be observed that the invention utilizes vaporized refrigerant at a predetermined constant pressure in a Venturi tube to withdraw the non-condensable gases from the low pressure absorber and transfer them to the high pressure condenser. It will still further be observed that the present invention provides a novel construction of apparatus for maintaining a column of liquid refrigerant of a predetermined height to balance the vaporized refrigerant to maintain the latter at a predetermined constant pressure.

While a preferred embodiment of the invention is herein shown and described as applied to a particular absorption refrigeration system, it will be apparent to those skilled in the art that the invention may be applied to other systems and that various modifications and changes may be made in the construction and arrangement of the parts thereof without departing from the spirit or scope of the invention.

What is claimed is:

1. In an absorption refrigeration system of the type which operates in a partial vacuum and utilizes water as a refrigerant and salt solution as an absorbent and in which non-condensable gases may occur, said system having one group of elements operable at low pressure and another group of elements operable at a higher pressure, means including liquid columns for maintaining the pressure differential between the groups of elements, and apparatus utilizing a portion of the refrigerant for transferring non-condensable gases from an element of the low pressure group to an element of the high pressure group in said system, said apparatus being connected to receive refrigerant from and return the refrigerant to said system.

2. In an absorption refrigeration system of the type having one group of elements operable at low pressure and another group of elements including a generator operable at a higher pressure, means for maintaining the pressure differential between the groups of elements, means

sorber through the conduit and transfer the gases to the condenser.

11. In an absorption refrigeration system of the type having one group of elements operable at low pressure and another group of elements operable at a higher pressure with means for maintaining the pressure differential between the groups of elements, a U-tube connected at its opposite ends to elements of the high pressure group, one leg of said U-tube being arranged to receive liquid refrigerant continuously to maintain a column of liquid therein, means for vaporizing the liquid refrigerant at the lower end of the U-tube to maintain vapor in the other leg of the U-tube at a pressure corresponding to the height of the liquid column in the first leg, and a device utilizing the vaporized refrigerant in the U-tube for transferring non-condensable gases from an element of the low pressure group to an element of the high pressure group.

12. In an absorption refrigeration system of the type having one group of elements operable at low pressure and another group of elements operable at a higher pressure with means for maintaining the pressure differential between the groups of elements, a U-tube connected at its opposite ends to elements of the high pressure group, said U-tube being arranged to receive liquid refrigerant at one end, a branch conduit adjacent the upper end of the U-tube for receiving liquid refrigerant, said branch conduit maintaining a liquid column in one leg of the U-tube of a predetermined constant height, means for vaporizing the liquid refrigerant at the lower end of the U-tube to maintain vapor in the other leg of the U-tube at a pressure corresponding to the height of the liquid column in the first leg, and a device utilizing the vaporized refrigerant in the U-tube for transferring non-condensable gases from an element of the low pressure group to an element of the high pressure group.

13. In an absorption refrigeration system of the type having an absorber operable at low pressure and a condenser operable at a higher pressure with means for maintaining the pressure differential between the condenser and absorber, a U-tube connected at its opposite ends to the opposite sides of the condenser, said U-tube being arranged to receive liquid refrigerant continuously at one end to maintain a column of liquid of predetermined height in one leg thereof, means for vaporizing the liquid refrigerant at the lower end of the U-tube to maintain vapor in the other leg thereof at a pressure corresponding to the height of the liquid column in the first leg, and a device utilizing the vaporized refrigerant in the U-tube for transferring non-condensable gases from the absorber to the condenser.

14. In an absorption refrigeration system of the type having one group of elements operable at low pressure and another group of elements operable at a higher pressure with means for maintaining the pressure differential between the groups of elements, a U-tube connected at its opposite ends to elements of the high pressure group, said U-tube being arranged to receive liquid refrigerant continuously at one end to maintain a column of liquid of predetermined height in one leg thereof, means for vaporizing the liquid refrigerant at the lower end of the U-tube to maintain vapor in the other leg thereof at a pressure corresponding to the height of the liquid column in the first leg, a conduit connected to an element of the low pressure group, a Venturi tube connected to the conduit and utilizing the va-

porized refrigerant in the U-tube for withdrawing non-condensable gases from the element of the low pressure group through the conduit and transferring the gases to an element of the high pressure group.

15. In an absorption refrigeration system of the type having one group of elements operable at low pressure and another group of elements operable at a higher pressure with means for maintaining the pressure differential between the groups of elements, a U-tube connected at its opposite ends to elements of the high pressure group, said U-tube being arranged to receive liquid refrigerant continuously at one end to maintain a column of liquid of predetermined height in one leg thereof, means for vaporizing the liquid refrigerant at the lower end of the U-tube to maintain vapor in the other leg at a pressure corresponding to the height of the liquid column in the first leg, a Venturi throat in the second leg of the U-tube, and a conduit connecting an element of the low pressure group to the Venturi throat, said vapor in the leg of the U-tube passing through the Venturi throat to withdraw non-condensable gases from the element of the low pressure group and transfer the gases to an element of the high pressure group.

16. In an absorption refrigeration system of the type having an absorber operable at low pressure and a condenser operable at a higher pressure with means for maintaining the pressure differential between the groups of elements, a U-tube connected at its opposite ends to the opposite sides of the condenser, said U-tube being arranged to receive liquid refrigerant continuously from the condenser at one end to maintain a column of liquid of predetermined height in one leg thereof, means for vaporizing the liquid refrigerant at the lower end of the U-tube to maintain vapor in the other leg of the U-tube at a pressure corresponding to the height of the liquid column in the first leg, a Venturi throat in the second leg of the U-tube, and a conduit connecting the absorber and Venturi throat, said vaporized refrigerant in the U-tube passing through the Venturi throat to withdraw non-condensable gases from the absorber through the conduit and transfer the gases to the condenser.

17. In an absorption refrigeration system of the type having an evaporator and absorber operable at low pressure and a generator and condenser operable at a higher pressure with means for maintaining the pressure differential therebetween, a U-tube connected at its opposite ends to the opposite side of the condenser, said U-tube being arranged to receive liquid refrigerant continuously at one end, a branch conduit adjacent the upper end of the U-tube for receiving liquid refrigerant and delivering it to the evaporator, said branch conduit maintaining a liquid column in the leg of the U-tube of a predetermined height, the lower end of the U-tube having coils surrounding the base of the generator to vaporize the liquid refrigerant therein to maintain vapor in the other leg of the U-tube at a pressure corresponding to the height of the liquid column in the first leg, and a device utilizing the vaporized refrigerant in the U-tube for transferring non-condensable gases from the absorber to the condenser.

18. In an absorption refrigeration system of the type having an evaporator and absorber operable at low pressure and a generator and condenser operable at a higher pressure, conduits connecting the condenser and evaporator and the

absorber and generator and arranged to maintain liquid columns therein to balance the differential in pressure, a U-tube connected at its opposite ends to the opposite side of the condenser, said U-tube being arranged to receive liquid refrigerant continuously at one end from the condenser, the conduit between the condenser and evaporator being connected to the U-tube adjacent its upper end to maintain a liquid column in one leg thereof of a predetermined height, means for vaporizing the liquid refrigerant in the lower end of the U-tube to maintain vapor in the other leg of the U-tube at a pressure corresponding to the height of the liquid column in the first leg, a Venturi throat in the second leg of the U-tube, and a conduit connecting the absorber and Venturi throat whereby vaporized refrigerant passing through the Venturi throat operates to withdraw non-condensable gases from the absorber and transfer them to the generator.

19. In an absorption refrigeration system of the type utilizing water as a refrigerant and a saline solution as an absorbent and operable in a partial vacuum, a generator, a condenser, an evaporator, an absorber, conduits connecting the generator, condenser, evaporator, and absorber to provide a closed circuit and arranged to provide pressure balancing liquid columns between the generator and condenser and evapo-

rator and absorber, a U-tube connected at its opposite ends to opposite sides of the condenser, said U-tube receiving liquid refrigerant at one end from the condenser to maintain a liquid column therein, means for vaporizing the liquid refrigerant at the lower end of the U-tube to produce refrigerant vapor in the other leg thereof at a pressure corresponding to the height of the liquid column in the first leg, a Venturi throat in the second leg of the U-tube, and a conduit connecting the absorber and Venturi throat whereby the vaporized refrigerant passing through the venturi operates to withdraw non-condensable gases from the absorber and transfer the gases to the condenser.
